UNITED STATES PATENT OFFICE.

CHARLES D. MACK, OF COOLEY, ARIZONA.

UNLOADING ATTACHMENT FOR CARS.

1,373,623.

Specification of Letters Patent.

Patented Apr. 5, 1921.

Application filed June 24, 1920. Serial No. 391,274.

To all whom it may concern:

Be it known that I, CHARLES D. MACK, a citizen of the United States, residing at Cooley, in the county of Apache and State 5 of Arizona, have invented certain new and useful Improvements in Unloading Attachments for Cars; and I do hereby declare the following to be a full, clear, and exact description of the same, reference being had to 10 the accompanying drawings, forming part of this specification.

This invention relates to platform cars particularly designed for the transportation of logs and has for one of its objects the provision of log retaining stakes and operating mechanism for releasing the stakes to permit unloading the logs, the operating mechanism being so arranged that it will be actuated by the application of the car brakes 20 whether they be applied by hand or by motive fluid derived from the locomotive or other suitable source.

A further object is the provision of a stake locking mechanism that can be readily applied to cars without the necessity of using attachments of unusual construction, thus greatly reducing the cost of manufacture and application of the invention to cars now in use.

30 In the accompanying drawings:

Figure 1 is a plan view of a car embodying the present invention;

Fig. 2 is an end view of the car;

Fig. 3 is a top plan view of one end of one 35 of the bunks, and

Fig. 4 is an end elevation of the parts shown in Fig. 3.

The logs, when loaded on the car, are supported on the transversely extending bunks 40 10, preferably of wood. The bunks are supported on trucks 11, 12 in the usual manner and the car is provided with a conventional form of braking mechanism. As shown in the present instance, the brake shoes are 45 moved into and out of engagement with the wheel treads through a series of connections by means of motive fluid supplied to a cylinder 14 from the locomotive, or the connections may, in the absence of motive fluid, be 50 actuated by hand brake 15. The connections between the cylinder 14 and the shoes of truck 11 consist of a link 16 connected at one end to a cross member 17 on which the shoes 13 are mounted and at the other end 55 to a link lever 18 pivoted to a second cross member 19 carrying brake shoes 20. Lever

18 is, in turn, connected to one end of a link 21, the opposite end of said link being pivotally connected to one end of a lever 22. Adjacent its opposite end lever 22 is pivotally secured to the actuating piston 23 of cylinder 14 while the brake rod 24, operable by a hand lever 15, is connected to the extreme end of said lever. The brakes shoes 13^a and 20^a of the other truck 12 are actuated by 60 a similar series of connections consisting of link 16^a, lever 18^a mounted on cross member 19^a, link 21^a and lever 22^a connected at one end to link 21^a. The other end of lever 22^a is pivoted on the car frame and intermediate its ends said lever is connected to 70 lever 22 by an equalizer bar 25 whereby when lever 22 is actuated to apply the brakes of truck 11 the brakes on the other truck will be simultaneously applied with equal 75 pressure, due to the floating connection between the lever 22 and equalizer bar 25, as is well understood and common in the art.

The stakes 26 for retaining the logs on the bunks 10 are mounted to swing in a vertical plane on pins 27 extending transversely through the bunks adjacent the ends of the latter, the pins 27 being retained in the bunks by any suitable securing means. Stakes 26 are mounted a little to one side of 85 their longitudinal centers so that when placed in a vertical position to engage logs loaded on the car their ends will project a considerable distance above the bunks and to normally lock the stakes in this position 90 pull pins 28 are slidably mounted in transversely extending openings in the bunks 10 below and a little to one side of pins 27. One end of each pull pin 28 normally projects beyond the side of the bunk and engages the lower ends of stakes 26 when the latter are in log engaging position but, as will be understood, withdrawal of the pull pins from engagement with the stakes will permit the stakes to swing downwardly to a 95 depending position. This movement of the stakes is augmented by the tendency of the logs to roll off upon the stakes being released, the car rails at the point where the logs are to be discharged being elevated one 100 above the other to give an inclination to the bunks 10.

To draw pull pins 28 out of engagement with the stakes the opposite ends of said pins are bifurcated and project beyond the 110 opposite sides of the bunks, these bifurcated ends being provided with alined apertures

29. Levers 30, pivoted intermediate their ends on brackets 31 secured in but projecting from the bunks 10, are each provided at one end with an aperture adapted to be brought into alignment with apertures 29, the levers and pins 28 being connected together by pivot pins 32 extending loosely through the registered apertures.

The opposite ends of levers 30 are pivotally connected to the brake mechanism, levers 30 on one side of the car being preferably connected to links 21, 21^a, respectively, and those on the other side to the brake rod 24. Application of the brakes causes the levers to move on their pivots in the directions indicated by arrows in Fig. 1 whereupon all of the stakes will be released and the logs discharged, the bunks being inclined as before described.

20 To prevent discharge of the logs should the brakes be applied before the cars reach their destination levers 30 and pull pins 28 are disconnected by removal of pivot pins 32 and the latter placed in apertures 33 in the ends of the pull pins where they remain until immediately before the cars reach their destination when the levers and pins are again connected. The pull pins are, of course, moved to their locking positions before they are disconnected.

This construction is simple, comparatively inexpensive to manufacture and can readily be placed on cars now in use with practically no alteration in the several parts of the cars and to avoid undue wear on the end portions of the bunks cheek plates 34, properly apertured, are positioned on opposite sides of the bunks as shown in Fig. 3, to prevent contact between the sides of the

bunks and the stakes, pull pin head, and 40 pivot pin head. By removably securing the several parts in the ends of the bunks any one of them may be taken out in case of breakage and a new part substituted.

I claim:

1. The combination with the brake actuating mechanism of a car, of a plurality of pivotally mounted car stakes on opposite sides of the car, means for locking said stakes in upright position, and connections 50 between said locking means and brake mechanism for releasing said locking means.

2. The combination with the brake actuating mechanism, of a plurality of transversely extending bunks, car stakes pivotally mounted on the bunks and extending in an upright position above the bunks, locking pins secured in the bunks and adapted to engage and hold said stakes in upright position, and connections between the brake 60 mechanism and locking pins whereby application of the brakes will disengage said pins from the stakes and permit the latter to assume a depending position below the bunks.

3. The combination with the brake actuating mechanism, of a plurality of transverse bunks, upwardly extending stakes pivotally mounted adjacent the ends of the bunks, pins extending through the bunks adapted to engage said stakes and lock 70 them in upright position, abutments on the bunks, and levers fulcrumed on said abutments, said levers being connected to said locking pins and the brake actuating mechanism whereby application of the brakes 75 will disengage the locking pins and release the stakes.

CHARLES D. MACK.
